US00D601153S

(12) **United States Design Patent**
Setiawan et al.

(10) **Patent No.:** US D601,153 S
(45) **Date of Patent:** ** Sep. 29, 2009

(54) **GRAPHICAL USER INTERFACE FOR COMPUTER SCREEN**

(75) Inventors: **Danny Setiawan**, Santa Monica, CA (US); **Ann-Bettina Colace**, Toluca Lake, CA (US)

(73) Assignee: **Yahoo! Inc.**, Sunnyvale, CA (US)

(**) Term: **14 Years**

(21) Appl. No.: **29/284,388**

(22) Filed: **Sep. 6, 2007**

(51) **LOC (9) Cl.** 32-00

(52) **U.S. Cl.** D14/485

(58) **Field of Classification Search** D14/485, D14/486, 487, 488, 489, 490, 491, 492, 493, D14/494, 495; D19/6; D20/11; 455/457; 715/212, 215, 221, 227, 235, 240, 243, 246, 715/277, 700, 716, 719, 727, 728, 730, 748, 715/750, 753, 756, 759, 762, 763, 768, 769, 715/771, 777, 779, 780, 781, 792, 793, 799, 715/800, 808, 809, 810, 825, 834, 835, 837, 715/840, 841, 842, 843, 846, 848, 851, 859, 715/860, 861, 864, 962, 964, 968, 969, 975; 345/440.2, 442, 22, 24, 902

(57) **CLAIM**

The ornamental design for a graphical user interface for computer screen, as shown and described.

DESCRIPTION

The sole FIGURE is a front view of our graphical user interface for computer screen showing our new design.

The broken line showing of a computer screen is included for the purpose of showing environmental structure and forms no part of the claimed design. The content inside of the broken line dot-dash lines form no part of the claimed design.

1 Claim, 1 Drawing Sheet
